(57) **CLAIM**

The ornamental design for a combined audio and video device, as shown and described.

DESCRIPTION

FIG. 1 is a front perspective view of a combined audio and video device showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines and unshaded areas illustrate portions of the combined audio and video device that form no part of the claimed design.

1 Claim, 7 Drawing Sheets(56)
